United States Patent Office.

A. H. SMITH, WILLIAM W. CLARK, AND GEORGE F. STARBUCK, OF NEW YORK, N. Y.

Design No. 2,766, dated August 20, 1867.

DESIGN FOR A HORSE-BRUSH.

The Schedule referred to in these Letters Patent and making part of the same.

TO ALL WHOM IT MAY CONCERN:

Be it known that we, A. H. SMITH, WILLIAM W. CLARK, and GEORGE F. STARBUCK, of the city, county, and State of New York, have originated and designed a new Design for an Ornament for Horse-Brushes, and that the following description, taken in connection with the accompanying drawing, showing a perspective view of our design hereinafter referred to, forms a full and exact specification of the same.

This invention relates to a new and original design for an ornament for a horse-brush, of that class which is constructed with a leather back; and it consists in having the back embossed with the head and neck of a horse, as hereinafter shown and described.

This brush may be constructed in any of the known forms, the shape or contour of which comprises no part of the design.

The leather back A is embossed with a horse's head, B, and neck C, as shown clearly in the drawing, and these parts are within a ring or raised annular bead, D, marked or ornamented to resemble a rope, the whole being at or about at the centre of the back of the brush.

Having thus described our invention, what we claim as new, and desire to secure by Letters Patent, is—
The design for an ornament for horse-brushes, substantially as shown and described.

A. H. SMITH,
WILLIAM W. CLARK,
GEORGE F. STARBUCK.
